UNITED STATES PATENT OFFICE.

SAMUEL S. WOODWARD, OF GUIDE ROCK, NEBRASKA.

LAMP-SHADE SUPPORT.

SPECIFICATION forming part of Letters Patent No. 334,502, dated January 19, 1886.

Application filed May 16, 1885. Serial No. 165,684. (No model.)

To all whom it may concern:

Be it known that I, SAMUEL S. WOODWARD, a citizen of the United States, residing at Guide Rock, in the county of Webster and State of Nebraska, have invented certain new and useful Improvements in Lamp-Shade Supports; and I do hereby declare the following to be a full, clear, and exact description of the invention, such as will enable others skilled in the art to which it appertains to make and use the same.

My invention relates to certain novel and useful improvements in lamp-shade supports; and it has for its object to provide a device of this description which may be readily attached to lamps of ordinary construction, which shall support the shade thereof at any desired height relative to the burner, and which, furthermore, may be used to suspend and uphold the body of the lamp; and with these ends in view my invention consists in the details of construction and combination of elements hereinafter fully explained, and then specifically designated by the claims.

In order that those skilled in the art to which my invention appertains may fully understand its construction, I will describe the same in detail, referring by letter to the accompanying drawings, forming a part of this specification, in which—

Figure 1 is a perspective view of my improvement; and Fig. 2 an enlarged detail of one of the posts, showing the form and method of attachment of the slide-brackets.

Similar letters denote like parts in both figures of the drawings.

A is a flat strip of metal bowed at its center to a broad U shape, and having its ends bent upward at right angles, to form the upright raked bars B. In turning up these bars I preferably fold the metal nearly upon itself, as will be readily seen by reference to Fig. 2. C is also a flat strip, bent into a loop at D, and having one end turned upon itself, for the purpose presently explained. The looped portion D corresponds, substantially, in contour to the bowed portion of strip A, and is riveted or otherwise secured thereto at E. The outer end of strip C is also bent upward in the same manner as the ends of strip A, and forms a third upright, B'.

F is a slide-link surrounding the horizontal portion of strip C, and adapted to slide over and inclose the free end of said strip where it is turned upon itself.

G are sliding spring-brackets bowed at the center, the upper end bent upwardly to form a retaining-spring, a, and the lower forming a hook, b, in which the edge of the shade may rest. These brackets are mounted upon the upright bars by two slots vertically aligned through the upper and lower sides of the bowed portion of the bracket, and through which the bars pass. These brackets hold upon the raked bars by the outer end of the slot through the upper side of the bow engaging with the racks upon the outer edge of the bar. The pressure of spring a against the inner edge of the upright tends to retain the slot in engagement with the rack, and the weight of the shade, when supported on the three hooks b, also furthers this result.

The brackets, as will be readily understood, may be readily slid up and down upon the bars, the latter motion being accomplished by releasing the slot from engagement with the rack, and so holding it during the downward movement of the bracket.

H are rings or hooks secured in holes in the upper ends of the uprights, and to these chains may be attached for the suspension of the device, if desired.

The operation of my improvement is as follows: The loop D in strip C is sprung around the collar of the lamp beneath the burner, and is held in that position by the slide-link inclosing and holding its free end against the body of the strip. The sliding brackets are then moved upon the uprights, and their hooks b serve to uphold the shade. If used as a hanging lamp, the uprights are suspended by chains or cords, when the device not only supports the shade, but the lamp as well. The shade, by different adjustments of the brackets, may be supported at any desired height relative to the burner or flame of the lamp.

Having thus described my invention, what I claim as new, and desire to secure by Letters Patent, is—

1. In a lamp-shade support, the combination, with the central loop, of the three or more horizontal arms attached to said loop,

bearing vertical racked bars, the brackets loosely mounted on the racked bars, provided with lips to carry the shade and lips to engage the teeth of the racked bars and secure the 5 vertical adjustment thereof, substantially as set forth.

2. The combination, with the strip C, bent upon itself to form the loop, and having its outer end bent upward at right angles and 10 racked, of the bowed strip A, whose ends are also racked and bent upwardly, and the sliding brackets adjustably mounted on the racked bars, and provided with lips to engage the shade, substantially as described.

15 3. In combination with the loop, the horizontal bars, and the racked vertical bars, the sliding brackets bowed and having vertically-aligned slots cut through the upper and lower sides of the bow for the admission of the bars,

having the upper end turned upward and 20 backward against the inner surface of the bar and the lower end provided with a lip to support the shade, substantially as specified.

4. The combination of strip A, bowed at the center and having both ends turned upwardly 25 and racked, strip C, bent upon itself, secured to the strip A, its outer end turned upward and racked, slide-link F, traveling thereon, the sliding brackets mounted on the bars, as described, and the rings or hooks H, secured 30 in the tops of the uprights, all for the purpose set forth.

In testimony whereof I affix my signature in presence of two witnesses.

SAMUEL S. WOODWARD.
